CURTAIN STRETCHER

Frank Edward Acker, Warrensville
Heights, Ohio

Application August 3, 1935, Serial No. 34,615

5 Claims. (Cl. 45—24)

The present invention relates to curtain stretchers or the like and particularly to frames for stretching netted curtains.

One of the objects of the present invention is to construct the side rails of the stretcher in such fashion that they provide abutments aligned with one another for slidably engaging and for retaining spaced transversely disposed curtain rods in position, also to provide for holding the side edges of the curtain in position while the side rails are spread, and also to connect the side rails with another by toggle-like linkage for spreading the rails.

In carrying out the foregoing object, it is a further object of the present invention to construct the rails of material which is substantially L-shaped in cross section, utilizing the vertically extending leg of the L-shaped rail for providing abutments for the curtain rods and utilizing the horizontally extending leg to carry the means for holding the side edges of the curtain.

Further objects and advantages will be apparent from the following disclosure, reference being had to the accompanying drawing wherein a preferred form of embodiment of the present invention is clearly shown.

In the drawing:

Fig. 1 is a top plan view of the improved stretcher carrying a single curtain, the full lines showing the position of the various parts in curtain stretching position and the dotted lines showing the position of the parts when a curtain is being attached;

Fig. 2 is a side view of Fig. 1;

Figs. 3, 4 and 5 are sectional views taken, respectively, on lines 3—3, 4—4 and 5—5 of Fig. 1, and

Fig. 6 is a view showing the stretcher collapsed and disposed within a storage box.

In the particular embodiment illustrated, the frame is formed in a unitary structure. The side rails or bars 20 and 21 are each formed of two sections, rail 20 including sections 23 and 24 and rail 21 including sections 25 and 26. Hinges 27 connect the sections of the specific rails and these hinges are disposed underneath the rails. Rail sections 23 and 24 each pivotally carry a hook 29 which is arranged to engage the under-side of headed studs 30 to hold the respective rail sections in aligned position.

It will be noted, particularly in Fig. 4, that the rails are substantially L-shaped in cross section, the lower or horizontal legs 31 of the L-shaped legs extending inwardly. These legs 31 carry the

means for engaging the side edges of the curtain and in the specific embodiment upwardly extending prongs or nails 34 are provided onto which the edges of the curtain are laced. The vertically extending legs 33 of the L-shaped rails 5 are each provided with a series of equally spaced abutments. These abutments may be formed by notching or as herein shown by drilling holes 35 in the legs 33. The holes 35 in rail 20 are aligned with the holes in rail 21 so as to receive 10 curtain rods 37 and 38 disposed transversely of rails 20 and 21.

For illustrating the principle of the present invention, it will be assumed that the rails 20 and 21 are in the dotted line position in which the 15 rails are indicated at 20a and 21a. The rods 37 and 38 are then inserted through the end hems 40 of curtain 41 or are laced onto the curtain. Then one end of the rod 37 is inserted through one of the holes 35 in rail 20. This insertion 20 will be from the inside of the frame. The rod 37 will then be drawn through the rail far enough to clear the leg 33 of rail 21 and then the rod will be moved in the opposite direction and into a hole 35 in rail 21. The hole selected will be in 25 alignment with the selected hole 35 of rail 20 so that the rod is disposed at right angles to rail 20 and 21. The length to which the curtain must be stretched being known, the curtain is stretched 30 by pulling on rod 38 and this rod is then inserted into the desired hole 35 in one of the rails and then into the hole in the other rail. Thus the curtain is stretched to the desired distance lengthwise. After the curtain is straightened on the rods, the edges thereof are fastened 35 to the prongs 34 and then the rails are spread.

For the purpose of spreading the rails 20 and 21, I have provided a toggle-like linkage and in the present embodiment, this linkage is disposed 40 at each end of the rails 20 and 21. Each linkage 43 and 44 includes two links, linkage 43 includes links 46 and 47 and the other includes links 48 and 49. Links 46 and 48 are hinged to opposite ends of rail 20 by hinges 50 and links 47 and 49 45 are hinged to opposite ends of rail 21 by like hinges 50. The inner ends of links 46 and 47 are connected with one another by hinge 52 and likewise the inner ends of links 48 and 49 are connected. 50

When the curtain is attached to the rails 20 and 21 as hereinbefore described, linkages 43 and 44 are in the dotted line position indicated at 43a and 44a. Then, when the center part of the linkage is forced inwardly, the rails 20 and 55

21 will be spread outwardly to stretch the curtain to its proper width. The links 46, 47, 48 and 49 are preferably each made of two pieces 54 and 55. Each piece 55 is provided with spaced holes 56 and each hole is adapted to receive a bolt 57. The bolts 57 extend through pieces 54 and are held from turning by a square shank 58. The pieces 54 and 55 are held in the selected hole position by wing nuts 59. Preferably, the top of pieces 54 are marked in inches so that the proper hole 56 can be selected to stretch the curtain to the known width desired. Likewise the tops of rails 20 and 21 are marked in inches so that the curtain can be stretched to the known length desired.

It will be noted that the ends of rails 20 and 21 and the adjoining ends of link pieces 54 are mitered. This miter is cut so that the linkages 43 and 44 are moved inwardly a short distance beyond their dead center positions whereby the tension of the stretched curtain or curtains can be utilized for holding the linkages in the widthwise curtain stretch position and, if desirable, a hook 58' can be pivotally attached to one piece 55 and a head stud 59' attached to the adjoining piece 55 to hook these pieces together.

The diameters of the rods 37 and 38 are less than the diameter of holes 35 so that the rails can slide readily relative to the rods when the rails are being spread. The prongs 34 are of sufficient length to hold several curtains disposed one above the other. In this manner several curtains can be dried simultaneously. It will of course be understood that separate sets of rods 37 and 38 will be provided for each curtain if the rods extend through the hems 40 and the rods of a set will then be placed in other holes 35 in rails 20 and 21.

Thus it is apparent that I have provided a curtain stretcher by which the curtain or a plurality of curtains can be stretched readily both lengthwise and widthwise and in which the curtains can be stretched to the desired dimension.

The entire stretcher can be collapsed to form a compact structure so that it and a number of curtain rods can be placed in narrow and short box 60. To fold the stretcher, the hooks 29 are first turned free of studs 30 and then one half of the stretcher is folded back on the other half as shown in dotted lines in Fig. 2. In this position linkages 43 and 44 overlie one another. The foregoing folding can be carried out either before or after the hooks 58 are released from studs 59 and the rails 20 and 21 are moved beside one another. After half of stretcher is folded back on the other half, the folded rails 20 and 21 are swung outwardly 180° to the position shown in Fig. 6 so that it will fit within box 60. The number of rods 37 and rods 38 are not shown in box 60 for the sake of more clearly showing the stretcher.

While the form of embodiment of the present invention as herein disclosed constitutes a preferred form, it is to be understood that other forms might be adopted, all coming within the scope of the claims which follow.

I claim:

1. In a curtain stretcher, the combination with a curtain, of a frame comprising spaced side

rails each having an abutment aligned with one another for slidable engagement with a transversely disposed curtain rod, similar abutments arranged spaced from the first abutments for slidable engagement with a second transversely disposed rod, means arranged along the length of the rails for holding the edges of the curtain, and toggle-like linkage connected with the rails for spreading the rails in a direction longitudinally of the rods.

2. In a curtain stretcher, the combination with a curtain, of a frame comprising spaced side rails each having an abutment aligned with one another for slidable engagement with a transversely disposed curtain rod, similar abutments arranged spaced from the first abutments for slidable engagement with a second transversely disposed rod, means arranged along the length of the rails for holding the edges of the curtain, and adjustable toggle-like linkage connected with the rails for spreading the rails in a direction longitudinally of the rods.

3. In a curtain stretcher, the combination with a curtain, of a frame comprising spaced side rails each being recessed in alignment with one another to provide abutments for slidable engagement with a transversely disposed curtain rod, similar recesses arranged in alignment with one another to provide abutments for slidable engagement with a second transversely disposed rod, means arranged along the length of the rails for holding the edges of the curtain, and toggle-like linkage connected with the rails for spreading the rails in a direction longitudinally of the rods.

4. In a curtain stretcher, the combination with a curtain, of a frame comprising spaced side rails, said rails being substantially L-shaped in cross section and the lower legs of said rails extending inwardly toward one another, the vertically extending legs each forming an abutment, the abutment of one leg being aligned with the abutment of the other leg for slidable engagement with a transversely disposed curtain rod, similar abutments arranged spaced from the first abutments for slidable engagement with a second transversely disposed rod, means on the lower legs of the rails and extending lengthwise of the rails for holding the edges of the curtain, and toggle-like linkage connected with the rails for spreading the rails in a direction longitudinally of the rods.

5. In a curtain stretcher, the combination with a curtain, of a frame comprising spaced side rails, said rails being substantially L-shaped in cross section and the lower legs of said rails extending inwardly toward one another, the vertically extending legs each forming an abutment, the abutment of one leg being aligned with the abutment of the other leg for slidable engagement with a transversely disposed curtain rod, similar abutments arranged spaced from the first abutments for slidable engagement with a second transversely disposed rod, a plurality of prongs extending upwardly from the lower legs of the rails for holding the edges of the curtain, and toggle-like linkage connected with the rails for spreading the rails in a direction longitudinally of the rods.
